FOOD WAGON OR THE LIKE

Robert Karoff, 222 4th Ave., New York, N.Y.

Filed July 23, 1959, Ser. No. 56,905

Term of patent 3½ years

(Cl. D44—24)

Fig. 2

Fig. 3

Figure 1 is a view in perspective of a food wagon or the like, embodying my new design and showing an umbrella, food receptacles and jars in phantom;

I claim:

The ornamental design for a food wagon or the like, substantially as shown and described.
